UNITED STATES PATENT OFFICE.

FORTONATO C. ZANETTI, OF BRYAN, TEXAS.

COMBINED FAUCET AND AUTOMATIC TOY.

SPECIFICATION forming part of Letters Patent No. 256,868, dated April 25, 1882.

Application filed February 28, 1882. (No model.)

To all whom it may concern:

Be it known that I, FORTONATO C. ZANETTI, of Bryan, in the county of Brazos and State of Texas, have invented certain new and useful Improvements in Combined Faucet and Automatic Toy; and I do hereby declare that the following is a full, clear, and exact description of the invention, which will enable others skilled in the art to which it appertains to make and use the same, reference being had to the accompanying drawings, which form a part of this specification.

Figure 1 is a perspective view of my invention as applied to the faucet of a soda-fountain. Fig. 2 is a longitudinal sectional view. Fig. 3 is a cross-section on the line *xx*, Fig. 2; and Fig. 4 is a longitudinal sectional view, illustrating a modification.

Corresponding parts in the several figures are denoted by like letters of reference.

This invention relates to faucets for soda-fountains and the like; and it consists in providing the same with a jointed figure or automaton adapted to be operated by the escaping fluid, as will be hereinafter fully described, and particularly pointed out in the claims.

In the drawings hereto annexed, A represents a faucet suitably attached to the soda-fountain B. Said faucet, which is mainly of the ordinary well-known construction, is provided with a suitably-constructed U-shaped gutter, C, extending diagonally in a downward direction from its outlet D, to guide the fluid as it escapes from the fountain into the tumbler held underneath.

E is a U-shaped bracket adjustable upon the trough or gutter C by means of hooks or lugs F upon its inner sides, which said hooks or lugs catch over the edges of said gutter. Bracket E is provided with suitable bearings for the shaft G of a paddle-wheel, H, adapted to be actuated by the liquid passing through the said trough or gutter. I is a jointed figure or automaton, which may, as in the drawings, represent a bicyclist, or it may be made to represent a steam-engine, windmill, organ-grinder, or whatever may be desired. Said automaton is also mounted, as shown, upon the bracket E and suitably connected with

cranks J upon the shaft of the paddle-wheel, 50 by which it is operated.

K is a spout or funnel, having a large flanged mouth or opening, L, and a screw-threaded ring, M, by which it may be adjusted upon the threaded end of the gutter C, which 55 is likewise formed with a ring, N. The flanged mouth of the funnel serves, when my invention is applied to fountains containing soda-water or other effervescent fluids, to prevent the same from overflowing, as it escapes from 60 the faucet, and the said funnel also serves, by pressing or bearing against the edge of the bracket E as it is being screwed into position, to prevent the said bracket from slipping or 65 sliding off the gutter or trough C.

In Fig. 4 of the drawings I have shown a faucet more especially adapted for fountains containing non-effervescent fluids—such as ice-water. In this case the flanged funnel K is omitted, and I substitute for it simply a ring, 70 O, which serves to hold the bracket E and its attachments in position.

This invention is simple, inexpensive, and easily applied to faucets now in use. It forms an amusing and attractive toy.

Having thus described my invention, I claim and desire to secure by Letters Patent of the United States—

1. A faucet constructed, as herein described, with a trough or gutter, in combination with an 80 automatic figure operated by a paddle-wheel adapted to be actuated by the fluid passing through said trough or gutter, as set forth.

2. The combination, with the faucet A, having trough C, of the funnel or spout K, having flange L, as set forth.

3. The combination of the faucet A, having trough C, the bracket E, paddle-wheel H, shaft G, automaton I, and the funnel or spout K, having flange L, substantially as and for 90 the purpose set forth.

In testimony that I claim the foregoing as my own I have hereto affixed my signature in presence of two witnesses.

FORTONATO CLEMENTE ZANETTI.
